UNITED STATES PATENT OFFICE.

HORACE HOLMES, OF STERLING, KANSAS.

SALT-BRINE EVAPORATOR.

SPECIFICATION forming part of Letters Patent No. 730,210, dated June 2, 1903.

Application filed February 24, 1902. Serial No. 95,207. (No model.)

To all whom it may concern:

Be it known that I, HORACE HOLMES, a citizen of the United States, residing at Sterling, county of Rice, State of Kansas, have invented a certain new and useful Improvement 5 in Salt-Brine Evaporators; and I declare the following to be a full, clear, and exact description of the invention, such as will enable others skilled in the art to which it pertains to make and use the same, reference 10 being had to the accompanying drawings, which form a part of this specification.

This invention relates to evaporators, especially evaporators of that class which is used to reduce brine and produce salt therefrom; and it has for its object improvements which relate to the construction of the pans and the means of applying heat to the brine contained in the pans, so as to utilize the heat 20 to the greatest extent.

In employing the invention the hot gases rising from combustion are used continuously and repeatedly until almost entirely cool, and all the heat utilized in the production of vapor, and even the vapor itself, is employed and the heat contained in it utilized for the 25 further evaporation of brine.

The mechanism employed to carry out the invention is shown and described in the following specification and in the accompanying drawings.

In the drawings, Figure 1 is a plan view with some of the cover parts broken away. Fig. 2 is a vertical cross-section of the pan C of Fig. 1. Fig. 3 is a vertical longitudinal section of the pan C of Fig. 1. Fig. 4 is a vertical cross-section of the pan A of Fig. 1. Fig. 5 is a side elevation of the raking mechanism used in pans A and B of Fig. 1. Fig. 6 is a plan view of the raking mechanism used in pans A and B of Fig. 1. Fig. 7 is a side elevation of the roller-rake used in pan C. Fig. 8 is a plan view of the roller-rake mechanism used in pan C. Fig. 9 is a perspective view of the economizer. Fig. 10 is a detail perspective showing the construction of the economizer. Fig. 11 is a section in the plane indicated by the line 11 11, Fig. 9. Fig. 12 is a section in the plane indicated by the line 12 12, Fig. 9. Fig. 13 is a horizontal section on the line 13 13, Fig. 4.

The apparatus may be described in general

terms as consisting of three covered evaporating-pans in brickwork setting, with a furnace for direct heating, with centrifugal fans 55 for creating necessary furnace-draft and for drawing off from the second and third pans in the series the vapors therefrom and for supplying to the surfaces of the liquid in the second and third pans a flow of air that is 60 necessary for low-temperature evaporation. There is combined with the pans and these means for producing air circulation under and over them a mechanical raking apparatus, which is employed to remove the salt as fast 65 as it is deposited.

The complete evaporator is composed of three parts or pans, each of which is used in a manner peculiar to itself, but which together comprise the complete mechanism employed to produce the finished product. A plan view of the three parts is seen in Fig. 1, in which pan A and pan B are employed to evaporate the brine by direct furnace-heat, the fire being under the pan A in the arch 75 which supports the pan. The hot gases pass through the bridge-wall into the chamber under the pan B, where they part with a portion of their heat to said pan, so that in the second pan B the evaporation of brine is effected by employing the residual heat from the furnace under the pan A, supplemented by a blast of hot air that is applied to the surface of the brine. In this pan the brine may not reach the boiling-point, but the residual 85 heat is utilized to produce as high a temperature as is possible. In the third pan C the brine is evaporated by means of heat that is derived from steam-coils, and these coils take their steam from the pan A through a pipe 90 50, Fig. 1, which extends from the pan A to the pan C and extends in coils at the top of the latter. They are aided by any residual heat that may have passed the pan B, as the gases of the combustion under the pan A are 95 carried under the pan C also; but they are carried through tubes, for reasons to be explained. In the pan C the heat from the steam-coils and the residual heat are aided by a hot-air blast applied to the surface. 100

The pan A is preferably rectangular in shape and flat-bottomed, except for a central longitudinal trough a, in which there is contained a link-belt conveyer b. The pan is set

on a double arch—that is, has a wall 1 at each side—and the middle of the pan is supported by a thick or double wall 2, and the trough *a* along the middle line of the pan A is sunk in the top of the wall 2. The pan is provided with a steam-tight cover, made, preferably, of sheet metal and made double, with an interposed layer of some non-conducting material that tends to prevent the rapid radiation of heat from the steam under the cover. The cover is preferably somewhat smaller than the pan, and its side flanges 3^a dip below the surface of the brine in the pan. It is held in position by suspension-cables 3^b, which run over suitable sheaves and are provided with counterweights to facilitate the handling of the cover. (The sheave and counterweights are not shown in the drawings.) It is intended to handle the cover by any suitable power-driven mechanism, which it is not thought necessary to show. The salt deposited from the brine in this pan is removed therefrom by a mechanical rake, a plan view of which is seen in Fig. 6. The rake consists of two pairs of horizontal bars 4^a and 4^b, one pair on each side of the pan, one rod of each pair being located at the top of the pan, where it may be easily connected to any suitable reciprocating part of the machinery, to which are given a reciprocating motion by a pitman connection. These bars are supported by the upper one of each pair resting on roller-brackets 4^c, and across the pan under them extends a carriage which carries two sets of scrapers. The carriage-body 5 is itself carried on rollers or wheels 5^a and 5^b, and it has pivoted to the side bars a triangular frame 6, which at the outer end is supported on a wheel 6^a. The wheel 6^a, which is itself on hinged legs, can assume a position in which its stem is vertical with respect to the bottom of the pan, in which case the wheel itself bears on the pan-bottom and the bracket 6 is lifted so that its outer or free end is elevated, and a scraper-blade 6^b, which is hung from the outer end, is raised off from the pan-bottom and will be carried over the salt on the pan-bottom without disturbing it. The parts assume this position automatically when the scraper is drawn to travel in the direction of the arrow 7. At the same time the opposed scraper 6^c drops to the pan-bottom and carries forward in front of it the salt on the pan-bottom and drops because the hinged caster-leg 6^c yields, the leg bends backward at the joint, the caster-wheel itself rises from the pan-bottom, and the lower part or heel part of the leg strikes the pan-bottom, but allows the arm 6 and the scraper-blade 6^b to drop. The carriage itself is not connected directly to the draft-rod 4^a, but is actuated by an auxiliary rod 4^b, that hangs below the draft-rod 4^a and below the brackets 4^c and is secured to the draft-rod by the hangers 51. On the carriage is a tilting draw-bar 8, provided with a balance-roll-carrying rider 8^a, the roll or wheel of which rides on the top

of the bar 4^b. The under part of the bar 4^b is provided at intervals with hangers 4^d, and the first action of the bar 4^b is to carry 7^c over the arm 8^a, swinging what has been the rear of the tilt-bar 8 downward out of engagement with the lug 4^d and swinging the end that had previously been to the front (but which is now about to be at the rear 75 with respect to the movement of the carriage) upward until it engages the lug 4^d. The carriage begins to move and the caster-wheel, which is now at the front and which is now off from the bottom of the pan, begins to swing to an 80 upright position, because of the engagement of the heel of the caster-leg with the pan, while the caster-wheel that is now at the rear begins to swing upward and the heel of the leg which supports this caster-wheel comes 85 into engagement with the pan-bottom; but the swinging arm drops and the scraper drops. The scrapers 6^b and 6^c are set at an angle to the long axis of the pan and force the salt from the sides of the pan inward into the 90 trough *a*, whence it is carried by the traveling carrier *b* and delivered eventually into a screw conveyer S.

The pan B is like pan A, so far as the construction of the pan itself is concerned, and 95 it also has the same raking attachment and it has a cover substantially the same as that to pan A. Pan C is differently constructed, and its construction will be best understood by examining Fig. 2. The bottom of this 100 pan is composed of a number of deep narrow flat-bottom troughs 11, 12, 13, and 14, which debouch into a transverse trough 15. In the transverse trough is a short screw conveyer S and at the end of the trough a link-belt 105 conveyer E.

The salt from each of the three pans is delivered by the chain conveyer forming a part of the raking mechanism, and each pan has a separate place of delivery. 110

The pan C is supported by the same side walls 1 continued. The intermediate wall, however, is omitted, and the chamber underneath the pan is occupied by flues placed crosswise the furnace, the open ends of which 115 flues communicate at one side of the furnace with a passage communicating with the chamber under the pan B and at the other side of the furnace with a passage, from which the gases are drawn by an exhaust-fan F¹ to 120 keep up the draft in the furnace. Opposite the open ends of the flues are stoppered openings 20 for the introduction of flue-cleaners. The bottom of the pan C is divided 125 into troughs to give it a greater heat-absorbing surface, and the flues are employed to furnish the greatest possible heat-radiating surface to the gases passing through them. Another object of using the flues at this point is to overcome the difficulties incident to the 130 destructive action or corrosive action of the cooling gases or burned bituminous coal. When these gases fall to a temperature such that the moisture contained in them con-

denses, they are seriously destructive and corrosive to iron, and by receiving the gases into the chamber 23 before they have reached this low temperature, thence conducting them through the less expensive and more easily renewable flues, their last heat element can be extracted without injury to the pan. The flues which may be injured can be easily and cheaply renewed.

10 In pan C there are in the pan coils of steam-pipes 24, to which steam is supplied from the surface of pan A through a pipe 50. The terminal of the steam-coil 24 extends into a vacuum-pump 25, which tends to produce a constant outflow from the pan A and prevents any pressure thereon.

In the pan C there is a gathering apparatus for salt in each of the troughs 11, 12, 13, and 14. This gathering apparatus has a roller-scaper—that is, the scraper consists of blades extending between disk-like terminals which serve as rollers, as seen in Fig. 7. The axis of the scraper is mounted on the reciprocating bar 27, and a dog 28 engages with the upper sides of one of the scrapers 29 and prevents the scraper from rolling when the bar is drawn in the direction of the arrow 30, but allows it to roll back without scraping on the return movement.

30 The vapor is drawn from the pans B and C by a centrifugal fan F through the pipes F' F² F³ and is discharged through a heater H, which I call an "economizer." In this the air passing to the pans is heated. This economizer consists of a number of sheets of metal, preferably of galvanized iron, which are arranged to form a series of rectangular chambers or cells, which are spaced by plates, and each of the cells is open at the two opposite ends. Above one cell is a second arranged at right angles to the first, and the open ends of this cell lie immediately above the closed side of the cell below and intermediately below the closed side of the cell above. The several cells so arranged form a cubical stack, any side of which shows the open ends of one half the constituent cells alternating with the vertical plates which form the closed sides of the other half of the cells. When two adjacent sides of the stack are provided with suitable separate breechings and a current of air is passed through the stack by means of suitable pipe connections, each of the sheets of metal which comprise the stack divides a volume of hot air from an equal volume of cold air. Thus the fan F draws the heated air and vapor from the pans B and C by the pipes F' F² and discharges it through one set of compartments in the economizer H, while the air and vapor thus exhausted is supplied by air flowing in through the other set of compartments in the economizer and passing to the pans B and C through the pipes H' H².

What I claim is—

65 1. In a brine-evaporator, the combination of a covered pan, means for heating the same to produce therein evaporation from the sur-

face at a temperature below the boiling-point, means for rapidly renewing the air above the surface of the brine and means for imparting 70 the heat of the air and vapor driven out of said pan to the air before it enters the same.

2. In a brine-evaporator, the combination of a plurality of pans in a series, a fire-arch under the first of the series to induce therein 75 evaporation by boiling, means for confining and conveying the furnace-gases to and under the other pans of the series to produce therein evaporation from the surface at a temperature below the boiling-point, means for 80 supplying the air essential to surface evaporation to the covered surfaces of brine in the later pans of the series, means for drawing off from said pans the hot saturated vapor arising from the contained brine, and means 85 for transferring the heat contained in said vapor to the dry air supplied to the said later pans of the series.

3. In a brine-evaporating plant, in combination with pans arranged to contain the brine 90 to be evaporated, a reciprocating scraper arranged to convey the salt of the sides toward the middle line of each pan, and an endless-belt conveyer arranged to traverse the middle line of said pan and convey the salt to, and 95 deliver it at the end of said pan, substantially as described.

4. In a brine-evaporating plant, in combination with a pan arranged to contain the brine, reciprocating scrapers arranged to convey the salt from the side to the middle line 100 of the pan, an endless-belt conveyer arranged to take the salt at the middle line and convey it to the end of the pan, and means for removing the salt from the end of the pan, substantially as described.

5. In a brine-evaporator, the combination of a series of pans adapted to hold brine, means for preventing the escape of steam and vapor generated in said pans except through means 110 for conveying it to the last pan of the series, means for conveying the steam generated in the first of a series of pans to the last pan of the series and there utilizing it as an auxiliary to other means for inducing evaporation 115 in the said last pan of the series.

6. In a brine-evaporator, in combination with a series of pans, a fire-arch under the first of said series, and under the last pan of said series, an air-chamber containing removable metal flues for the conduction of the furnace-gases, and the incidental heating of the confined air contained in said chamber and the transmission to the liquid in the pan of the heat of said air; the increment of heat 125 thus transmitted from the furnace-gases to the liquid in said pan being auxiliary to other differently-derived portions of heat used to promote evaporation of said liquid.

7. In a brine-evaporator, in combination 130 with a series of salt-evaporating pans, a cover arranged to close in each of said pans, a fire-arch under the first of said pans, means for confining the steam generated in the first of

said pans and for utilizing it as an auxiliary source of heat in the last pan of the series, a means of confining the vapor in the second and third pans of the series, and of utilizing it to heat the air which is caused to circulate over the surface of the brine in said second and third pans, constituting an evaporative force auxiliary to the fire-heat supplied to the

second pan, and the steam and residual heat of furnace-gases supplied to the third pan. 10

In testimony whereof I sign this specification in the presence of two witnesses.

HORACE HOLMES.
